US00D669073S

(12) **United States Design Patent**
Wu et al.

(10) **Patent No.:** **US D669,073 S**
(45) **Date of Patent:** **** Oct. 16, 2012**

(54) **DATA TRANSMISSION DEVICE**

(75) Inventors: **Chin-Yi Wu**, Taichung (TW);
Sheng-Chung Chen, Hsinchu County (TW)

(73) Assignee: **Arcadyan Technology Corporation**, Hsinchu (TW)

(**) Term: **14 Years**

(21) Appl. No.: **29/393,397**

(22) Filed: **Jun. 3, 2011**

(51) **LOC (9) CL. 14-02**

(52) **U.S. CL. D14/358; D14/240**

(58) **Field of Classification Search** D14/300-302, D14/313, 314, 341, 348-370, 383, 385, 432, D14/435, 436, 496, 125, 135, 137, 155, 240-242, D14/299; D3/201, 273; D18/56; D10/65, D10/75, 78; D13/103, 149, 162, 184, 199; 361/679.31, 679.33, 679.4, 752; 711/100, 711/115

(57) **CLAIM**

The ornamental design for a data transmission device, as shown and described.

DESCRIPTION

FIG. 1 is a perspective view of a “data transmission device” showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
